DESIGN FOR A CONTROL STATION ENCLOSURE

Jean Otis Reinecke, Chicago, Ill., assignor to
Allen-Bradley Company, Milwaukee, Wis., a
corporation of Wisconsin

Application October 2, 1939, Serial No. 87,483

Term of patent 14 years

To all whom it may concern:

Be it known that I, Jean Otis Reinecke, a citizen of the United States, residing at Chicago, Cook County, and State of Illinois, have invented a new, original, and ornamental Design for a Control Station Enclosure, of which the following is a specification, reference being had to the accom-

panying drawing, forming part thereof.

The figure is a view, in perspective of a control station enclosure, showing my new design.

I claim:

The ornamental design for a control station enclosure, as shown.

JEAN OTIS REINECKE.
